ICE HANDLING APPARATUS

Marion S. Jones, Baltimore, Md.

Application June 22, 1939, Serial No. 280,630

15 Claims. (CL 214—1)

This invention relates to apparatus for handling ice and it is designed more especially for use in ice manufacturing plants.

As is well known to those skilled in the art the blocks of ice, as they are produced, are taken into a storage room where they are compactly stacked for future use. This work generally has been done by hand and, because of the weight of the ice blocks it has been difficult 5 to place the blocks in proper positions on end in the storage room and it has been even more difficult to perform this service without scarring or otherwise mutilating the blocks with the tongs used.

10 In my copending application, No. 242,101, filed November 23, 1938, there has been disclosed an apparatus for receiving blocks of ice after they leave the can, standing the blocks on end, and positioning them where they can be moved readily into the storage room. The apparatus referred to is designed primarily for handling a 15 number of blocks of ice simultaneously and is of such a nature as to require assembly of the parts and more or less construction work incidental thereto.

An object of the present invention is to provide an ice handling apparatus which can be delivered as a complete unit and, while useful in plants of all sizes, is especially desirable in 20 connection with ice manufacturing plants where the production is rapid.

A further object of the invention is to provide a self-contained unit of this character which, when properly placed in position relative to the 25 ice block carrier usually employed, will operate automatically to receive a block of ice, while in a prone position, stand it on end, discharge it onto a delivery platform, and then automatically reset itself in position to receive another block.

Another object is to provide an ice handling 30 unit of this character which is simple in construction, can be installed readily, and will not easily get out of order.

With the foregoing and other objects in view 35 which will appear as the description proceeds, the invention consists of certain novel details of construction and combinations of parts hereinafter more fully described and pointed out in the claims, it being understood that changes may be 40 made in the construction and arrangement of parts without departing from the spirit of the invention as claimed.

In the accompanying drawings the preferred 45 form of the invention has been shown.

50 In said drawings:

Figure 1 is an elevation showing the delivery side of the ice handling unit, the parts being shown in their normal positions.

Figure 2 is a central vertical longitudinal section therethrough, the position of the tiltable 5 platform and parts associated therewith during the delivery of a standing block of ice, being indicated by broken lines.

Figure 3 is a section on line 3—3, Figure 1.

Figure 4 is an enlarged section on line 4—4, 10 Figure 1.

Figure 5 is a horizontal section through the unit above the tiltable platform with the parts in the positions assumed thereby during the delivery of a block of ice while standing on end. 15

Figure 6 is a section on the line 6—6, Figure 2.

Figure 7 is a view in diagram showing the motor circuit.

Referring to the figures by characters of reference, 1 designates the bed of the unit formed 20 preferably of suitably connected angle members, the sides of the base being joined solely at the ends so that an unobstructed space is left between the sides extending throughout the length of the bed or base. Superposed parallel rails 2 25 and 3 extend inwardly from the upper portion of each side of the bed and these rails cooperate to provide a track in which is movably mounted a carriage 4 having an upwardly extending portion 5 the top 6 of which constitutes a seat proportioned to receive and support the lower end of 30 a block of ice while in an upright position.

The carriage 4 is normally positioned upon the receiving end of the unit as shown in Figures 1 and 2 and supported under the carriage by one 35 side of the bed 1 is a stub shaft 7 on which is mounted a sprocket 8. A drive shaft 9 extends into the bed 1 from one side thereof and has a sprocket 10 secured to it. An endless chain 11 is mounted on the two sprockets and carries a 40 wrist pin 12 which is joined by a connecting rod 13 to the carriage 4 as shown at 14. Thus when chain 11 is driven by the rotating sprocket 10 and drive shaft 9, the wrist pin 12 will transmit motion to the connecting rod 13 and will travel 45 from the position shown by full lines in Figure 2 to the position shown by broken lines in said figure, thereby causing the carriage 4 to move longitudinally along its track from one end to the other of the bed. As the chain continues 50 to operate, it will thrust through the rod 13 against the carriage and move said carriage back to its initial position as shown by full lines in Figure 2.

A superstructure 15 is erected rigidly on the 55

bed 1 and is open at the front end, as shown at 16, so that a block of ice while in a prone position, will be able to move through said open end and into the unit. The other end and the sides 5 of the superstructure are open except for a rigid side plate 17 which extends from the back end of the superstructure forwardly to a point adjacent to the center thereof. This side plate has a cam slot 18 therein extending from a point adjacent to the lower portion of the forward end of the plate and curved abruptly in an upward direction, this upwardly curved portion 19 merging at an abrupt angle into a horizontally arranged extension 20 of the slot leading toward the back end of plate 17. The walls of the slot can be strengthened by means of flanges 21 or the like which cooperate to form a cam track.

Shaft 9 is actuated preferably by an electric motor 22 which can be located at any desired point and can be coupled to the shaft by any means provided for that purpose. Included in the motor circuit is a switch 23 of the well known ratchet type which, in the present instance, is adapted to be opened and closed by successive 25 thrusts in one direction against a switch lever 24.

Supported in the superstructure 15 is a switch actuating lever 25 one end 26 of which is located adjacent to lever 24 of the switch while the other end can be connected by a rod 27 to a bell crank 30 28 fulcrumed adjacent to one side of the carriage 4 where it can be tripped by a pin 29 extending laterally from the upwardly extended portion 5 of the carriage. In other words when this carriage is moved away from the position shown in Figure 2, pin 29 will slip past the bell crank 28 and swing the end 26 of lever 25 downwardly away from switch lever 24. However, when the carriage 4 is moved from the broken line position shown at the left of Figure 2 to the full line position shown at the right of said figure, the pin 40 29 will wipe past the bell crank 28 and actuate it so as to cause the bell crank to thrust upwardly through the end 26 of lever 25 against switch lever 24 and thus shut off the current to the motor.

The upwardly projecting portion 5 of the carriage 4 has extending ears 30 to which is pivotally connected the frame 31 of a platform 32. This platform has an upstanding frame 33 at one side 55 closed by a side plate 34. The other side of the platform is open and the same is likewise true of the front end of the platform which is that end facing the inlet opening 16 of the superstructure 15. The back end of the platform is provided with a transverse abutment 35 extending throughout the width of the platform and extending from one side of frame 30 is a bearing shaft 36 carrying a roller 37 which is seated in slot 18. When the platform 32 is in its normal position, as shown in Figures 1 and 2, the front end thereof is supported by the pivot pin 38 while the other end thereof is supported by the roller 37 seated in cam slot 18. Platform 32 is normally below the level of the seat 6 and that end 65 of the seat nearest the platform 32 is preferably rounded as shown at 39.

Located below and connected to the platform 32 is a tripping lever 40 one end of which is weighted as indicated at 41 while the other end 70 has a head 42 extending upwardly through a slot 43 in the platform between the sides thereof.

The lever 40 which is in the nature of a broad plate, is provided near one side with an extension 44 to which is pivotally connected a rod 45 75 the upper end of which is pivotally attached to

one end of a lever 46 fulcrumed, between its ends, as at 47, on a plate 48 located above the opening at the front or receiving end of the platform structure. This lever, in turn, has a plunger 49 pivotally attached to its other end and this plunger, which is guided within the framework of the platform structure, is normally positioned at one side of the end 26 of lever 25 and below the switch lever 24.

Spaced brackets are secured to the top portion 10 of the side frame 33, as shown at 50 and mounted for rotation in these brackets is a shaft 51 to which are secured parallel arms 52 adapted to move with the shaft. A crank arm 53 is secured to and extended laterally from shaft 51 and is 15 connected by a rod 54 to the short arm of a lever 55. This lever, which is fulcrumed at 56, is extended along the outer side of the plate 34 as indicated by broken lines in Figure 2 and a spring 57 is secured at one end to the lever and at its 20 other end to the frame 33 so as to exert a constant upward pull upon that end portion of the lever connected to the rod 54. The other end of lever 55 extends adjacent to one side of the forward end of platform 32 and is so located that 25 when the platform is tilted and moved backwardly as hereinafter explained, said end of the lever will come against a stop bracket 58 carried by the bed 1 and as indicated by broken lines in Figure 2.

The arms 52 are preferably joined rigidly as at 59 so as to form a frame and this frame is extended between L-shaped ejector members 60 to which they are connected by a pivot shaft 61. The ejector members are joined by cross slats 62 35 and the ejector formed by these members and slats is normally positioned as shown in Figure 3 with one end portion extending downwardly adjacent to the plate 17 while the other end portion is extended laterally toward the open side of the 40 superstructure 5 so as to overlie the platform 32. The free ends of the overlying portions of ejector members 60 are connected by links 63 to the top portion of the frame 33 of the platform so that under normal conditions the arms 52 and 45 links 63 cooperate with the top portion of frame 33 and the upper portion of the ejector formed by member 60 and slats 62, to form a parallelogram.

A delivery platform 64 is extended laterally 50 from the open side of frame 15 to such position that it will be substantially flush with the seat 6 of the carriage 4 when said carriage is brought to its rear position as indicated by broken lines in Figure 2. A feed chute 65 is positioned to receive ice blocks in prone position as they are supplied to the inlet opening 16 and this chute is inclined downwardly over but out of contact with the seat 6 and, when the platform 32 is in its normal position, as shown in Figure 2, ice 60 sliding in a prone position along the chute 65 will be delivered in said position on the platform 32.

As has been stated heretofore the present apparatus is to be made in a self-contained unit 65 to be sold complete to producers of large blocks of ice such, for example, as formed ordinarily in cans. These blocks, after being formed are delivered to a carrier (not shown) which drags the blocks in prone position along a platform for delivery to the storage room. Ordinarily it has been necessary to handle these blocks by hand after they leave the carrier and the exertion required to stand them on end has been excessive. Furthermore the tongs used for handling the 75

blocks has frequently marred them by chipping and scarring the surfaces. Instead of providing men for standing the blocks on end as they leave the conveyer, the present apparatus is to be installed at the point where the blocks of ice are successively delivered from the carrier or conveyer. It is intended to so locate the inlet openings 16 that each block of ice as it arrives in a prone position opposite the opening, will be free to slide through the opening and thrust into chute 65 and thence along the chute to the platform 32. Sliding movement of the block on the platform will be limited by the abutment 35. Assuming that the motor switch is open, it will be noted that as soon as the prone block of ice is delivered to platform 32, it will press downwardly onto the head 42 of lever 40 and this will cause the extension 44 of the lever to pull downwardly through rod 45 upon lever 46 which, in turn, will thrust upwardly through rod 39 against switch lever 34 so as to close the circuit to the motor. As the motor is operatively connected to shaft 9, it will immediately drive the shaft and this will cause the chain 11 to travel in the direction indicated by the arrow in Figure 2. Consequently the connecting rod 13 which is coupled to the chain, will pull on the carriage 4 and cause the carriage to move backwardly away from the inlet chute 55. This movement will cause the roller 37 to travel rearwardly and upwardly within slot 18 until it reaches the upper extension 20 of this slot whereupon the roller will travel rearwardly in a substantially horizontal direction. During this movement of the roller the platform 32 will be swung to an angle of ninety degrees so that the block of ice, which was prone on the platform 32, will be swung upwardly until one end thereof is brought to rest upon the seat 6. At the same time the ejector is swung from the position shown by full lines in Figure 2 to the position shown by broken lines in said figure and as the carriage begins to move backwardly after the platform has been swung to ninety degrees, lever 55 comes against the stop bracket 58 and is actuated against the tension of spring 57. Thus motion is transmitted from the lever through rod 54 to the crank arm 53 and shaft 51 is caused to turn. As the frame made up of arms 52 and their connections 59 is rigidly secured to this shaft 51, said frame will be caused to swing toward the open side of the unit with the result that the ejector formed by the members 60 and the slats 62 will engage two surfaces of the block 55 of ice which is in standing position and slide said block off of platform 32 and onto the delivery platform 64. From this point the block can be slid by hand into the storage room.

Following the delivery of the block of ice as described, the connecting rod 13 is carried forwardly by wrist pin 12 after it moves around the rear sprocket 10 so that said rod 13 will thus thrust against the carriage and move it and the connected parts back to the initial or starting position as shown in Figure 2. During this operation lever 55 will move away from bracket 58 so that spring 57 can return the ejector and other parts associated therewith to their initial positions. Roller 37 will travel forwardly in extension 20 of slot 18 and thence downwardly in the curved portion 19 of the slot until the platform 32 reassumes the position shown in Figure 2. As the carriage approaches its starting point the bell crank 28 is engaged by pin 29 so as to be actuated with the result that motion will be

transmitted therefrom through rod 27 and lever 25 to the switch lever 24 which thus will be actuated to shut off the current to the motor. The apparatus is thus reset ready to again move through another cycle of operation such as has been described.

It will be obvious that as soon as the block of ice is moved into an upstanding position, the weight thereof is removed from head 42 of lever 40 so that when the platform 32 is restored to its 10 normal position, said lever and the parts controlled thereby will return to their normal positions.

In order to effect strong connections between the links 63, ejector members 60, and frame 33, 15 it is preferred to extend the pivot shaft transversely through these parts as shown at 66.

A stirrup 67 can be connected to the carriage so as to extend downwardly therefrom and move under the lower flight of chain 11 to prevent the lower flight of the chain 11 from sagging under the weight of the rod 13. This shaft will move forwardly adjacent to the wrist pin 12 as it travels from sprocket 10 to sprocket 8.

Resetting of the ejector can be aided by a 25 stop bracket 58 located close to and movable with platform 32. This is positioned so as to engage the end of lever 55 and thrust up upon it when the parts are brought to normal or starting positions, thereby holding the ejector 30 positively in full retracted position.

Obviously the apparatus herein described can be built as a complete unit, shipped to the point of use, and quickly set up at any point where it is convenient to receive the prone blocks of 35 ice delivered from the carrier platform commonly employed in ice manufacturing plants.

What is claimed is:

1. The combination with a stationary structure having an inlet, of a carriage slidable in the structure, a platform hingedly connected thereto and normally positioned to receive a prone block of ice from the inlet, a motor, means operated by the motor for moving the carriage and platform away from the inlet, motor starting 40 mechanism positioned for actuation by a prone block of ice when directed onto the platform, and cooperating means on the stationary structure and the platform for swinging said platform during the movement of the carriage, said 45 platform being positioned to deposit the supported ice block on end upon the carriage.

2. A self-contained ice handling unit including a stationary structure having an inlet, a carriage slidable in the structure, a platform 55 hingedly connected to the carriage and normally positioned to receive a prone block of ice from the inlet, a motor, means operated by the motor for moving the carriage and platform away from and towards the inlet successively, motor starting 60 mechanism positioned for actuation by a prone block of ice when directed onto the platform, cooperating means on the stationary structure and the platform for swinging said platform in one direction during the movement 65 of the carriage away from the inlet, said platform being positioned to deposit the supported ice block on end upon the carriage during the completion of said swinging movement, said cooperating means on the structure and platform 70 constituting means for returning the platform to its initial position during the movement of the carriage toward the inlet, and means operated by the carriage while approaching the inlet 75 for stopping the motor.

3. A self-contained ice handling unit including a stationary structure having an inlet at one end and a side outlet, a carriage slideable in the structure between the inlet and the outlet, a platform hingedly connected to the carriage and normally positioned to receive a prone block of ice from the inlet, a motor, means operated by the motor for moving the carriage and platform from the inlet and toward the outlet, motor starting mechanism positioned for actuation by a prone block of ice when directed onto the platform, and cooperating means on the stationary structure and the platform for swinging said platform during the movement of the carriage toward the outlet, the said platform being positioned to deposit the supported ice block on end upon the carriage while approaching the outlet.
4. A self-contained ice handling unit including a stationary structure having an inlet at one end and a side outlet, a carriage slideable in the structure between the inlet and the outlet, a platform hingedly connected to the carriage and normally positioned to receive a prone block of ice from the inlet, a motor, means operated by the motor for moving the carriage and platform from the inlet and toward the outlet, motor starting mechanism positioned for actuation by a prone block of ice when directed onto the platform, and cooperating means on the stationary structure and the platform for swinging said platform during the movement of the carriage toward the outlet, the said platform being positioned to deposit the supported ice block on end upon the carriage while approaching the outlet, an ejector movable with the carriage, and means controlled by the movement of the carriage relative to the stationary structure for actuating the ejector while adjacent to the outlet.
5. A self-contained ice handling unit including a stationary structure having an ice inlet and an ice outlet, a carriage slideable in the structure, a platform hingedly connected thereto and normally positioned to receive a prone block of ice from the inlet, a motor, means operated by the motor for moving the carriage and platform from the inlet toward the outlet and back to the inlet successively, motor controlling mechanism positioned for actuation by a prone block of ice when directed onto the platform, thereby to start the motor, cooperating means on the stationary structure and the platform for swinging said platform upwardly during the movement of the carriage toward the outlet, said platform being positioned to deposit the supported prone block on end upon the carriage during the completion of said swinging movement, an ejector movable with the platform, means operated by the movement of the platform relative to the carriage for ejecting the ice block through the outlet from the carriage, said cooperating means on the stationary structure and platform being operable to return the platform to its initial position during the movement of the carriage toward the inlet, means released by the movement of the carriage toward the inlet for returning the ejector to its normal position, and means controlled by the carriage on reaching the inlet, for stopping the motor.
6. A self-contained ice handling apparatus including a carriage, a track therefor, a motor for moving the carriage back and forth, means for controlling the actuation of the motor, a platform movably connected to the carriage, means for directing a prone block of ice onto the platform, means operated by the block of ice when deposited on the platform, for actuating the motor, means controlling the movement of the carriage, thereby to start the motor and propel the carriage and platform, means for swinging the platform while the carriage is moving in one direction to transfer the prone block of ice to an upstanding position on the carriage, and means controlled by the movement of the carriage in one direction for ejecting the block of ice from the carriage.
7. A self-contained ice handling unit including a carriage, a track therefor, a motor for imparting back and forth movement to the carriage, a platform movably connected to and movable with the carriage, means for directing a prone block of ice onto the platform, means controlled by the ice when deposited on the platform for starting the motor, thereby to move the carriage and platform together in opposite directions successively, means for swinging the platform relative to the carriage when the platform is moved in one direction thereby to transfer the prone block of ice into an upstanding position on the carriage, said means operating to return the platform to normal position when the carriage is moved in the opposite direction, and means controlled by the movement of the carriage in one direction for ejecting the block of ice from the carriage after being deposited thereon by the platform.
8. A self-contained ice handling unit including a carriage, a track therefor, a motor for imparting back and forth movement to the carriage, a platform movably connected to and movable with the carriage, means for directing a prone block of ice onto the platform, means controlled by the ice when deposited on the platform for starting the motor, thereby to move the carriage and platform together in opposite directions successively, means controlled by movement of the platform in one direction for swinging it relative to the carriage thereby to transfer the prone block of ice into an upstanding position on the carriage, said means operating to return the platform to normal position when the carriage is moved in the opposite direction, and means controlled by the movement of the carriage in one direction for ejecting the block of ice from the carriage after being deposited thereon by the platform, and means operated by the carriage upon the completion of one of its movements for stopping the motor.
9. In an ice handling apparatus a carriage, a track therefor, an endless chain, a connection between said chain and the carriage, a motor for actuating the chain, said chain and connection constituting means for reciprocating the carriage, a platform hingedly connected to the carriage, means for directing a prone block of ice over the carriage and onto the platform, means actuated by the block of ice when deposited on the platform for starting the motor, means cooperating with the platform for swinging it relative to the carriage during the movement of the carriage in one direction thereby to transfer the prone block of ice from the platform to an upstanding position on the carriage, and means controlled by the carriage upon completing its movement in the opposite direction for stopping the motor.
10. In an ice handling apparatus a carriage, a track therefor, an endless chain, a connection between said chain and the carriage, a motor for actuating the chain, said chain and connection constituting means for reciprocating the carriage,

- a platform hingedly connected to the carriage, means for directing a prone block of ice over the carriage and onto the platform, means actuated by the block of ice when deposited on the platform for starting the motor, means cooperating with the platform for swinging it relative to the carriage during the movement of the carriage in one direction thereby to transfer the prone block of ice from the platform to an upstanding position on the carriage, an ejector movable with the platform, means controlled by the movement of the platform and carried in one direction for actuating the ejector to expel the upstanding block of ice from the carriage, and means operated by the carriage upon the completion of its movement in the opposite direction, for stopping the motor.
11. Ice handling apparatus including a stationary structure, a cam carried thereby including an upwardly curved portion merging into a substantially horizontally extended portion, a carriage mounted for back and forth motion, a motor, means actuated by the motor for imparting back and forth motion to the carriage, a platform hingedly connected to the carriage and normally positioned to receive a prone block of ice, means carried by the platform for moving engagement with the cam, said means and cam cooperating to swing the platform relative to the carriage during the movement of the carriage in one direction, thereby to transfer the prone block of ice on the platform to an upstanding position on the carriage, means operated by the block of ice when deposited on the platform, for starting the motor to drive the carriage and platform in said direction to swing the platform, and to subsequently return the platform and carriage to their starting positions, and means controlled by the carriage on reaching its starting position, for stopping the motor.
12. Ice handling apparatus including a stationary structure, a cam carried thereby including an upwardly curved portion merging into a substantially horizontally extended portion, a carriage mounted for back and forth motion, a motor, means actuated by the motor for imparting back and forth motion to the carriage, a platform hingedly connected to the carriage and normally positioned to receive a prone block of ice, means carried by the platform for moving engagement with the cam, said means and cam cooperating to swing the platform relative to the carriage during the movement of the carriage in one direction, thereby to transfer the prone block of ice on the platform to an upstanding position on the carriage, means operated by the block of ice when deposited on the platform, for starting the motor to drive the carriage and platform in

said direction to swing the platform, and to subsequently return the platform and carriage to their starting positions, an ejector movable with the platform, means controlled by the sliding movement of the platform in one direction for actuating the ejector to shift the block of ice from the carriage, means released by the movement of the carriage toward its point of starting for returning the ejecting means to initial position, and means operated by the carriage on reaching its point of starting for stopping the motor.

13. The combination with a carriage and a motor operatively connected thereto for reciprocating the carriage, of a platform hingedly connected to the carriage, means for swinging the platform relative to the carriage during the movement of the carriage in one direction for transferring a prone block of ice upon the platform to upstanding position on the carriage, and means controlled by the movement of the carriage and platform in one direction for ejecting the block of ice on the carriage.

14. The combination with a carriage and a motor operatively connected thereto for reciprocating the carriage, of a platform hingedly connected to the carriage, means for swinging the platform relative to the carriage during the movement of the carriage in one direction for transferring a prone block of ice upon the platform to upstanding position on the carriage, and means controlled by the movement of the carriage and platform in one direction for ejecting the block of ice on the carriage, said ejecting means including separate angular members, slots connected therebetween, a rock shaft movable with the platform, arms secured to the shaft and pivotally connected to said members, links connecting said members and positioned for cooperation with the arms to form substantially a parallelogram, a spring-restrained lever movable with the platform, an operative connection between said lever and the rock shaft, and means positioned for engagement by the lever following the swinging movement of the platform and during the movement of the carriage for actuating said lever and the rock shaft, said ejector being positioned to engage and thrust against the block of ice upstanding on the carriage.

15. In ice handling apparatus a platform tiltably mounted, means for directing a block of ice in a prone position into the platform, means for tilting the platform to up-end the block, and means controlled by the tilting of the platform while up-ending the block, for ejecting the up-ended block laterally from the platform.

MARION S. JONES.
